UNITED STATES PATENT OFFICE

2,514,801

PAPER CRIMPER AND STACKER

Gerald G. Sapp, Damascus, Va.

Application September 13, 1948, Serial No. 49,087

15 Claims. (Cl. 154—30)

1

This invention relates to a novel device for forming straight fold edges in sheets of material and has for its primary object to crimp or corrugate and stack sheets of paper, such as employed in the manufacture of honeycombs, in a uniform and reliable manner.

Another important object of this invention is to provide a machine for crimping a continuous strip of paper or similar pressable sheets of other material, such as sheet metal, cardboard or the like, which will be automatic in operation to receive a continuous strip of material at one end, convey the strip from a supply source, such as a roll, drum or the like, and simultaneously form folds in the strip and stack the strip, after fold formations, in a die or box at the other end.

Another important object of this invention is to form folds in thin sheets of material in a non-injurious manner so that the danger of ripping or tearing or otherwise damaging the sheets is avoided and the folds are formed accurately and evenly.

Another important object of this invention is to provide a device, having interrelated meshing means for engaging a continuous strip of material and forming folds therein, said means being evenly moved into engagement of the strip and maintained under pressure in said engagement for a predetermined period of travel.

A meritorious feature of this invention resides in the combination of a pair of upper and lower carriers, having a plurality of transversely disposed teeth, which are moved into meshing engagement responsive to movement of the carrier and travel of the teeth over actuating means, with means provided for retaining the teeth in meshing engagement for a predetermined path of travel.

Yet another important feature of this invention resides in the provision of means for resiliently anchoring the complementary teeth in transverse position between a pair of lower chains and a pair of upper chains or conveyors, the upper and lower chains having a parallel travel path in close relation so that the teeth are juxtaposed for a certain path of travel and are moved into meshing engagement responsive to actuation of idler pulleys disposed in the path of travel of the teeth and engageable with operating members extending outwardly from the teeth.

These and ancillary objects and other meritorious features to become more fully apparent upon a perusal of the following description are

2

attained by this invention, a preferred embodiment of which is set forth in the following specification and illustrated in the accompanying drawings, wherein:

- 5 Figure 1 is a vertical sectional view taken on a central longitudinal plane through the machine, showing a portion of the teeth and appurtenant structure in section, with the opposite side of the frame for the machine shown in elevation;
- 10 Figure 2 is a vertical sectional view taken on the transverse plane of line 2—2 of Figure 1 and looking in the direction of the arrows;
- 15 Figure 3 is a view in perspective of the housing or casing transversely disposed in spaced formation between the set of carriers and adapted to adjustably house the crimping teeth;
- 20 Figure 4 is an enlarged sectional view taken substantially on the plane of line 4—4 of Figure 3;
- 25 Figure 5 is an enlarged sectional view taken on line 5—5 of Figure 2;
- 30 Figure 6 is an enlarged sectional view, illustrating the meshing engagement of the complementary upper and lower teeth, the same being disposed in coactive pressing engagement on a continuous strip of material, and
- 35 Figure 7 is a view in perspective of the means provided for receiving the crimped or corrugated strip of material.
- 40 The paper crimping machine, generally designated by the reference character 10 and generally illustrated in Figures 1 and 3 comprises a base platform 12 upon which are mounted a pair of laterally opposed end standards or posts 14 and a similar end pair 16. Each of the longitudinally opposed posts of the pairs 14 and 16 are rigidified and connected by longitudinally extending brace bars 18 and 20, which also serve as supporting means for appurtenant structure of the machine.
- 45 Axles or shafts 22, 24, 26 and 28 are transversely disposed between the pairs of end standards, as seen in Figure 1, with the extending end of each of the axles rotatably journaled in conventional journal boxes or the like 30, and the shafts 22 and 24 placed in spaced vertical alignment between the pair of posts 14 and the shafts 26 and 28 placed in longitudinal alignment therewith between the posts 16. A pair of transversely aligned and spaced sprockets 32 or similar gear or drive transmitting members are secured on the shaft 22 and a similar pair of sprockets 34 are carried by the shaft 26 in longitudinal alignment with the sprockets 32. A pair of chains 36 and 38 are trained over and communicate

with the sprockets, the entire assembly defining an upper pair of carriers or endless conveyors 40. In an identical fashion, a lower pair of carriers or conveyors 42 is provided and has a similar path travel in close relation with the upper pair. The lower pair of carriers comprises a pair of transversely aligned sprockets 44 carried by the shaft 24 and a complementary pair 46, carried by the shaft 28 with endless conveyor or chains 48 or similar flexible connecting members connected with the respectively longitudinally aligned sprockets of the pairs 44 and 46. The chains 36 and 48 are formed in a similar manner and comprise a plurality of parallel links 50 which are interconnected by solid bars 52 pivotally connected between the opposing ends of the parallel links, as seen in Figure 3.

A plurality of channel members 54, constituting housings or casings, are transversely disposed between the upper and lower pairs of chains. For this purpose, the channel members are formed at their opposing extremities with extending flanges 56 and 58 which are apertured as at 60 to receive a connecting member, such as a rivet or the like 62, in association with the bars 52. Thus, the teeth housings are rested on the transversely opposing pairs of chains in a depending manner.

The channel members 54 serve as housings or casings for the teeth 64, as seen in Figures 3, 4 and 6. The housings or casings 54 have parallel opposed side walls 66 and 68 joined by a straight bottom wall 70 and having an open top. The opposite ends of the bottom wall 70 are offset forming extension casings 72 and 74. The teeth 64, as seen in Figure 6, are generally A-shaped and have a square bottom or base portion 76, the opposing sides 78 and 80 of each of the teeth running upwardly and inwardly and converging at the minor point or apex 82, so that the major portion of the teeth is of triangular configuration. However, the sides 78 and 80 are parallel at the base or square portion so that the same slidably engage the side walls 66 and 68 of the casing 54, which is necessary to assure the rigid and upright position of the teeth at all times and to control the outward directional movement of the teeth, during the paper crimping operation, as will be later described.

The bottom surface of the base portion of each of the teeth is adapted to overlie the extension casings 72 and 74, as seen in Figure 4. In this respect, the ends of each of the elongated teeth are resiliently mounted in the casing 54 by means of the compression springs 84 which are connected between the end wall of the extension casings 72 and 74 and the bottom surface of the base portion 76 of each of the teeth, adjacent the opposing ends of the teeth. Thus, the teeth are normally held entirely within the casing 54 but can be urged outwardly by an external force and then returned to the casing through the urging of the springs 84.

Means is provided for raising the teeth from their respective similar casings or housings 54 responsive to the travel path and movement of the upper and lower pairs of carriers or conveyors. The means provided comprises a pair of oppositely extending operating studs or fingers 86 and 88 which are disposed through vertical slots 90 in the end walls of the casings 54, as seen in Figures 3 and 4. The studs extend integrally from each of the teeth through the guide slots 90 and function to move the teeth upwardly from the casing 54 responsive to movement of the studs over a

cam surface. Thus, any suitable means may be provided, that could be conveniently and easily journaled in the path of travel of the teeth and would be adaptable to engage the studs, which would ride upon and over the means and thereby raise the teeth corresponding and coincidentally with the movement of the upper and lower pair of chains or carriers.

In this respect, a pair of transversely opposed upper idler wheels or pulleys 92 are provided and a similar lower pair 94 is provided, the idler wheels 92 and 94 being disposed in vertical alignment, as seen in Figure 2. The idler wheels, of course, are smaller in diameter than the main sprockets 44 and 46 and are disposed rearwardly from the center point of the drive sprockets so that the teeth are at all times in an upright position when the studs 86 and 88 engage and travel on the annular periphery of the wheels. A pair of arms 96 are adjustably carried by the pair of longitudinally extending brace bars 18 through the medium of a laterally extending spindle 98 which is transversely inserted through the bars 18 and adjustably held in the desired position by means of the set screws 100, which vertically penetrate the bars 18 and engage the pin 99. At the opposite or angularly depending ends of the arms 96 are laterally extended stub axles or the like 102, upon which the idler wheels 92 are journaled.

In a similar fashion, the pair of lower idler wheels 94 are adjustably held in an angularly raised position in complementary alignment with the idler wheels 92, as seen in Figure 5.

It can be appreciated that the idler wheels can be easily adjusted so as to govern and control the raised movement of the teeth 64. Thus, depending upon the desired depth of fold and the type of material, the idler wheels can be located in any adjusted position so that the studs 86 and 88 are forced, in their movement on the circumference of the wheels, to move the needed distance in the guide slots 90 and thereby raise the teeth 64.

Suitable means is provided for maintaining under a definite pressure, the inter-engagement or meshing engagement of the upper and lower sets of teeth, carried by the upper and lower pairs of conveyors, as seen in Figure 1, and preferably comprises a pair of upper, parallel outwardly turned channel bars 104 and 106 which longitudinally extend the desired distance in cooperative adjacency to a similarly disposed pair 108 and 110. The meshing engagement of the teeth is retained by the travel of the studs 86 and 88 over the opposing surfaces of the vertically opposed bars, as appreciated upon viewing Figure 2. The retaining bars 104, 106, 108 and 110 are rigidly maintained in the desired position through the medium of a plurality of bracing bars 112 which vertically extend from the brace bars 18 and 20 and are bolted to the retaining bars, as seen in Figures 2 and 5.

The operation of this machine is believed ascertainable, with respect to Figure 1 of the drawings. A roll of pressible material 120 is conventionally maintained under a certain amount of tension at one end of the upper and lower pairs of carriers and the material is fed from the roll into a passageway 122, which is defined by the close parallel travel path of the upper and lower pairs of conveyors or carriers 40 and 42. Of course, the upper and lower pairs of chains or belts have the same rotating travel path. As the chains are rotated by the set of sprockets, the transversely disposed teeth are brought into relation with the cams or idler wheels. The extend-

ing studs on the teeth, which are vertically disposed prior to engagement of the cams or wheels, engage the cams and ride up and over the periphery thereof. The travel of the studs on the cams or wheels raises the teeth and places the upper and lower sets of teeth in meshing engagement on the strip of material. The teeth are maintained in the coactive pressing relationship by the bars 104 and 106, 108 and 110, which receive the studs from the cams or idler wheels. Of course, the length of the retaining bars, upon which the studs travel, would be dependent upon the desire of the operator or the specification of the job. When the studs arrive at the terminating point of the bars, the teeth are sharply withdrawn from the crimped paper by means of the springs 84.

As the teeth crimp the paper and move the paper or sheet of material in the passageway 122 from the roll or drum 120, the teeth also convey the crimped sheet or material to a die or stacking box 124, which is disposed horizontally at the opposite end of the passageway. Thus, the meshing engagement of the teeth functions not only to crimp the paper and convey the paper or sheet of material through the passageway but also functions to move the crimped paper into the stacking box 124, so that the sheet of material leaving the belt is pushed into and through the box.

It is to be particularly noted that the studs when coming in contact with the cams or idler wheels or pulleys gently raise and lower the teeth of the two carriers until full meshing engagement is obtained with the sheet between the two sets of teeth, the teeth maintaining this position by the extended studs transferring off the idler wheels onto the slide bars of equal height for any desired distance. The gradual raising and lowering of the teeth in contact with the paper prevents any tearing of the paper or prematurely crimping thereof. The springs 84 distinctively and certainly withdraw the teeth from meshing position so that uniform and accurate fold lines are formed in the sheet of material.

Of course, glue lines may be applied to the sheet of material before going to the crimpler and the lines can be protected during the crimping operation by providing gaps or openings in the teeth at the required spacing.

In view of the drawings and foregoing description and operation, it is believed that the novelty and merits of this invention will become apparent to those skilled in the art. However, since various uses of this device are possible, it is to be understood that certain changes in the structure for moving the teeth and raising and lowering the teeth in meshing engagement on a strip of material can be effected, the same coming within the spirit of the invention and the scope of the appended claims.

Having described the invention, what is claimed as new is:

1. A machine for crimping paper comprising a pair of upper and lower endless carriers having a parallel travel path in close cooperative relation, a plurality of transverse members disposed between the upper and lower carriers forming a passageway for a continuous strip of paper, interengaging means operatively connected with said members for cooperatively engaging the strip and moving the strip through the passageway and simultaneously forming folds therein, means for moving said foregoing means into interengagement with the strip, means extending

along the passageway for retaining said strip engaging means in engagement with the strip and means connected between said transverse members and the strip engaging means for withdrawing said means from said engagement with the strip.

2. A machine for crimping paper comprising a plurality of upper and lower complementary members having a parallel travel path in close relation forming a passageway for a strip of paper, interengaging teeth carried by said members for engaging the strip and moving the strip in the passageway and simultaneously forming folds therein, means disposed in the path of travel of said teeth for moving said teeth into complementary engagement with the strip, means for retaining said teeth in said engagement for a predetermined path of travel and resilient means connected between said members and the teeth for withdrawing the teeth from engagement with the strip.

3. A machine for crimping paper comprising a pair of upper and lower juxtaposed endless carriers having a parallel path of travel, channel members transversely disposed between said carriers forming a longitudinal passageway for a strip of continuous paper, teeth disposed in said channel members for engaging the strip and moving the strip through the passageway simultaneously forming folds therein, means for pressing said teeth cooperatively on the strip, means for retaining said teeth in pressing engagement and release means connected between the channel members and said teeth.

35 4. A machine for crimping paper comprising a set of cooperatively spaced upper and lower pairs of endless conveyors having a parallel path of travel, channel members transversely disposed on said pairs of conveyors, teeth resiliently mounted in said channel members, means for pressing said teeth into meshing relation, and means for retaining said teeth in said relation for a predetermined travel period.

5. In a machine for crimping material an upper and lower set of complementary channel members having a parallel path of travel in close relation forming a passageway for a continuous strip of material, teeth resiliently mounted in said channel members, means for raising said teeth from the channel members and pressing the teeth into complementary fold forming engagement of the strip, means for retaining said teeth in said relation, and means for withdrawing the teeth from said relation.

6. In a paper crimping device, a plurality of resiliently mounted teeth disposed in complementary opposed relation, means for urging said teeth into meshing engagement and means for retaining the teeth in said engagement.

60 7. A paper crimping and stacking machine comprising a pair of upper and lower endless conveyors having a parallel path of travel in close relation forming a passageway for a continuous strip of material, a die disposed at one end of the passageway, channel members transversely carried by said conveyors, teeth resiliently anchored in said channel members, means for raising said teeth from the channel members into meshing engagement in the passageway for forming folds in the strip of material and conveying the multi-folded strip to the die and means for retaining said teeth in said engagement for a predetermined path of travel.

70 8. The combination of claim 7, wherein said means for raising the teeth includes cams jour-

nailed in the path of travel of the teeth, studs extending from said teeth and engageable on the periphery of the cams.

9. The combination of claim 7, wherein said means for retaining the teeth in meshing engagement includes guide bars longitudinally disposed between the conveyors and positioned in the passageway.

10. A paper crimping and stacking machine comprising a pair of upper and lower endless conveyors having a parallel and adjacent path of travel forming a passageway for a continuous strip of material, a receiver box disposed at one end of the passageway, interengaging teeth transversely carried by the conveyors, means for moving said teeth into meshing engagement of the strip for forming folds in the strip and packing the multi-folded strip in the receiver box, means extending longitudinally in the passageway for retaining said teeth in said engagement for a predetermined path of travel and means for moving said teeth vertically out of engagement with said strip at the receiver box end of the passageway.

11. A paper crimping and stacking machine comprising a pair of complementary conveyors having a parallel and adjacent path of travel forming a passageway for a continuous strip of material, intermeshing teeth transversely carried by the conveyors, means for moving said teeth into meshing engagement of the strip, means extending longitudinally in the passageway for retaining the teeth in said engagement for a predetermined path of travel and resilient means for moving said teeth in a vertical plane out of intermeshing engagement with the strip.

12. A paper crimping and stacking machine comprising a pair of complementary conveyors having a parallel and adjacent path of travel forming a passageway for a continuous strip of material, intermeshing teeth transversely carried by the conveyors, adjustable cams disposed adjacent said passageway for moving said teeth into meshing engagement of the strip, means for moving said teeth into meshing engagement of the strip, means extending longitudinally in the

passageway for retaining the teeth in said engagement for a predetermined path of travel and resilient means for moving said teeth in a vertical plane out of intermeshing engagement with the strip.

13. A paper crimping and stacking machine comprising a pair of endless conveyors having a parallel path of travel in close relation forming a passageway for a continuous strip of material, members transversely carried by said conveyor, interengaging teeth resiliently carried by said members, means for moving said teeth into intermeshing engagement of the strip, said teeth forming folds in the strip and moving the same through the passageway and means extending longitudinally in the passageway for holding the teeth in intermeshing engagement of the strip for a predetermined path of travel.

14. In a material crimping machine, an endless conveyor, a plurality of transverse members carried by the conveyor, teeth resiliently mounted on the members, adjustable cams operatively engageable with said teeth for raising the teeth from the members and means for retaining said teeth raised from the member for a predetermined path of travel.

15. In a material crimping machine, an endless conveyor, a plurality of transverse teeth carried by the conveyor, means for resiliently mounting the teeth on the conveyor, means for raising said teeth from the conveyor and means for retaining said teeth in a raised position for a predetermined path of travel.
